UNITED STATES PATENT OFFICE.

HERMAN F. STRAW, OF MANCHESTER, NEW HAMPSHIRE.

MECHANISM FOR WINDING YARNS UPON SHUTTLE BOBBINS OR QUILLS.

SPECIFICATION forming part of Letters Patent No. 313,124, dated March 3, 1885.

Application filed August 8, 1883. (No model.)

To all whom it may concern:

Be it known that I, HERMAN F. STRAW, of Manchester, county of Hillsborough, State of New Hampshire, have invented an Improvement in Mechanism for Winding Yarns upon Shuttle Bobbins or Quills, of which the following description, in connection with the accompanying drawings, is a specification, like letters on the drawings representing like parts.

10 This invention, relating to bobbin-winding machines, has for its object the production of a novel organization of mechanism for winding upon shuttle bobbins or quills the chain-dyed and beamed filling, as referred to in my application, No. 100,545, for United States patent, filed July 11, 1883, to which reference may be had. In this my improved machine the dyed filling-yarn wound upon a yarn-beam is led, preferably each thread separately, through 15 or between wires, dents, or pins of a raddle, from which latter the said threads are led through the eyes of a traverse-bar and between feeding-rollers, after which the threads pass over a suitable rest and through eyes of 20 a traverse-rail, and then are wound upon bobbins driven by friction, as will be described, the said feed-rollers being extended lengthwise of the machine. The spindles which rotate the bobbins are provided each with a 25 flange, and each spindle is driven by a whirl loose thereon, the upper flat side of each whirl acting against a friction-washer, preferably of felt, interposed between the said whirl and the flange fixed on the spindle, the adhesion 30 or friction between the flange, washer, and whirl causing the bobbin to rotate and effect the winding of the filling thereon. By driving the bobbin frictionally instead of positively, the filling is always kept taut, and the 35 40 nose and all parts of the yarn-load are made of sufficient hardness to avoid tangling when the filling is being unwound from the bobbin.

Figure 1 is a plan view of my improved bobbin-winding machine, which one conversant with ordinary spinning machinery may understand; Fig. 2, a section of the same on the dotted line xx , Fig. 1; and Fig. 3, an enlarged section taken through the bobbin, footstep, whirl, the sleeve, the washer, and flange of the spindle, the spindle being in elevation.

The beam b , containing the filling a , wound upon it, as described in my other application

above referred to, after being dyed, has its journals b' placed in suitable bearings, b'' , attached to the stand b^3 , suitably fastened to the floor, 55 and for the best results the said beam b has its longitudinal axis in the direction of the length of the machine and of the rows of spindles to be described.

The raddle, supported upon adjustable up- 60 rights c^3 , held by screws c^4 , is composed of a curved or bow-shaped bar, c , provided with dents c' , or other usual guiding and separating devices for the threads.

The frame-work A of the winding-machine 65 has at its center, and extended longitudinally through the machine, a shaft, B , which is provided with the usual "tin" or spindle-driving drum, C , about which are extended the bands d , which drive the loose whirls e , which 70 surround the spindles s , placed in long rows along the sides of the machine in the direction of its length. Each whirl has a sleeve, e' , which is extended down into the bolster and step-case f , supported in the bolster-rail 75 e^2 , and the said sleeve bears by its periphery against the inner surface of the bolster and step-case f , and receives the spindle s loosely. The case f has a shoulder on which rests the lower end of the sleeve of the whirl, to thus 80 keep the under side of the whirl above the end of the said case. The said bolster and step-case serve as an oil-well, and the sleeve of the 85 whirl acts as a bolster for the spindle s . The spindle s has a flange fixed on it, and above 90 the same I have shown a cup, h' , into the open top of which the lower end of the bobbin h^2 is inserted, the said bobbin in practice being of any usual shape commonly employed to hold filling-yarn in loom-shuttles. The bobbin is driven by this cup by friction, but may be driven by a button, or by adhesion to the spindle, as in ordinary spinning-frames.

Between the whirl and the flange h , attached to the spindle, is a felt or other suitable washer, m , capable of exerting such friction that the said flange and the spindle and bobbin will derive rotation from friction exerted between the whirl and the said washer and flange. The size of the washer may be varied to determine the amount of friction. The whirl will be driven by the band from the drum at the requisite speed. The spindle does not rest at its lower end on the step, but is sup-

ported vertically by the flange resting on the friction-washer only. For the best results the whirl will be rotated at such speed as to rotate the bobbin with little or no slip when 5 the filling is being wound upon that part of the bobbin of smallest diameter; but as the filling is being wound upon a part of the bobbin of greater diameter, or upon the yarn-load of increasing diameter, and the delivery of 10 the yarn being at substantially a constant uniform speed, it follows that the bobbin must run more slowly than when the filling is being wound upon the smallest part.

The above arrangement obviates the break- 15 age of filling, which would result if the bobbin were driven always at the same speed. The bobbin is made to drag or fall behind the speed of rotation of the whirl, this being practically accomplished by making the whirl 20 loose on the spindle, so that the spindle and bobbin may be driven frictionally by the action of the whirl on the washer and flange. By the employment of the frictionally-driven 25 bobbin the latter may lag behind more and more as the diameter of the yarn-load is increased; or as the filling is going from one part of the bobbin to another part thereof of greater diameter the latter is made to drag by 30 the tension of the yarn, which is being delivered at a constant rate, and in this way the filling may and will always be wound taut upon the bobbin from end to end of the yarn-load, and there will be made what is known as a 35 "solid compact nose," or one which will not tangle or break down when unwinding in a shuttle.

The tin or spindle-driving drum C is driven by a band upon a pulley, B', or in other usual manner, and the shaft B, near the end of the 40 said drum, has a suitable pulley, B², (see Fig. 1,) which by band B² and pulley B', or by other suitable connection, drives the feed-roller p, the shaft 10 of which rests in suitable bearings on the stands 16 on the frame A.

The counter-shaft, by which the tin-drum 45 shaft is driven, will in practice contain a fast and slow motion device, such as commonly employed on slashers and warpers, by means of which the speed of the machine may be reduced, so as to enable the operator to readily 50 mend threads and clear the rolls of threads which have wound around them, and not stop the machine. Above the roller p is a covered or soft roller, 11, and above it a pressure-roller, 12. Each filling-thread from the beam b and raddle c is passed through an ordinary guide-eye, 2, secured to the lower side of the shifting-bar 3, supported by guide-arms, and connected by rod 4 with the pin of a crank, 5, 55 on shaft 6, held in bearings 7, the said shaft having fast on it a worm-wheel, 8, engaged at its lower side by a worm, 9, fast to the shaft 10 of the feed-roller p. The crank 5 causes the reciprocations of the bar 3, and the attached eyes 2 cause the filling-thread to be 60 moved backward and forward a little between the faces of the rollers p and 11, so that the

cover of the latter will not be worn unevenly. The filling-yarn passed through the eyes 2 is then passed between the rollers 12 and 11, 70 and thence between rollers 11 and p, and the individual threads are turned alternately in different directions, as in Figs. 1, 2—one part over each of the guides o at opposite sides of the frame—and from the said guides 75 each of the filling-threads is passed through a suitable eye, n', in a traverse-rail, g, and is attached to the bobbin opposite the said eye, there being a spindle and eye for each thread or pair or more of threads, if they are to be 80 doubled on the quill.

The traverse-rail g, mounted on suitable lifting-rods, i, held in suitable bearings attached to the frame-work, will be lifted by the usual builder mechanism common to many 85 spinning-frames—such, for instance, as represented in United States Letters Patent No. 186,322, January 16, 1877, wherein the bobbins are wound for filling, and wherein the lifting-rods are marked i, it being understood 90 that the lifting-rods i in the machine herein described may be guided and raised and lowered by mechanism such as shown and described in the said patent, or by any other usual devices. The speed of the feed-rollers 95 11 and p, as well as of the drum C and whirl, is constant, one depending upon the other; but the speed of the spindle driven by friction, as described, is made variable, being gradually slower as the traverse-rail descends, and vice 100 versa, in order to wind the yarn properly and avoid breaking the same.

In Fig. 1, I have omitted most of the spindles, deeming it necessary to show but a few of them, as they are all alike.

In practice I employ two series of spindles in each side of the frame, one above and a little back of the other. The axis of the yarn-beam is substantially parallel with or in the direction of the length of the rows of spindles, and the raddle, extended in the same general direction, is elevated above the head of the operator, so that the latter can move about the side of the machine to doff the bobbins or mend broken yarns.

For the successful operation of any machine for winding chain-dyed filling bobbins or quills for loom-spindles, it is necessary, first, that the machine should have a sufficient number of spindles—say from three to four hundred— 120 so that the chain as made for dyeing may have a sufficient number of threads to be economically handled in the dyeing and beaming processes; secondly, that the various parts of the machine should be so arranged that all 125 parts of the beam, every spindle, and the whole length of each thread from the yarn-beam to the spindle should be readily accessible to the operative for the purpose of mending breakages and for doffing the bobbins; thirdly, the parts should be so arranged that if a thread breaks while the machine is running the broken thread will not tangle in with and break down others; fourthly, that the rolls for

drawing the yarn from the beam and delivering the same to the spindles should be as near as possible to the spindles, so that the threads can be readily kept taut and straight between the yarn-beam and the said feed-rolls by means of friction applied to the yarn-beam, while the tension on the thread after leaving the feed-rolls must depend entirely on the frictional spindles; and, further, the yarn, practically in one sheet, between the yarn-beam and feed-rolls must be drawn by the latter, that the strain exerted on the sheet will be distributed on all the yarns of the sheet to the advantage of the weaker yarns, while, after leaving the feed-rolls, the threads must be drawn separately downward in opposite directions and wound upon the bobbin by the friction of the spindle, each individual thread being exposed to single strain only for the short distance between the feed-rolls and spindles; and, lastly, the spindle and friction for driving the bobbin must be such that the strain on the threads can be made practically the same on each of the threads going to the spindles, and that, too, without causing great trouble to the operative or requiring any delicate adjustment; and this friction must also be such that, with the spindle moving at from two to three thousand turns per minute, the bobbin can fall behind the speed of the whirl at least one-half while the yarn is winding on the largest diameter of the quill, while at the same time the friction must be strong enough and even enough to wind a compact and hard quill in all parts.

I am aware that machines have been devised and described in patents for winding yarn from beams onto spools, but none of them, so far as I am aware, contain the mechanical organization herein described and specifically claimed. I have herein shown and described a spindle driven by friction; but such is not herein separately claimed, as it forms the subject-matter of application No. 140,850, filed

45 August 18, 1884.

I claim—

1. The combination, substantially as shown and described, of the yarn-beam, the curved raddle arranged above the beam, its adjusting devices, the reciprocating eye-bar 3, feed-rollers to draw the thread from the beam under the guidance of the raddle and the reciprocating bar, and the spindles and means to drive them.

55 2. The combination, substantially as shown and described, of the yarn-beam, the curved raddle arranged above the beam, its adjusting devices, the reciprocating eye-bar 3, feed-rollers to draw the thread from the beam under the guidance of the raddle and reciprocating bar, the guides *o*, traverse-rail *g*, and the spindles and means to drive them.

3. The combination, substantially as shown and described, of the yarn-beam, the curved raddle arranged above the beam, its adjusting

devices, the reciprocating eye-bar 3, feed-rollers to draw the thread from the beam under the guidance of the raddle and reciprocating bar, the guides *o*, the traverse-rail *g*, the spindles, means, as set forth, to drive them, and 70 friction-washers interposed between the spindles and their driving means to hold the spindles frictionally, as set forth.

4. The combination, substantially as shown and described, of the yarn-beam, the curved 75 raddle arranged above the beam, its adjusting devices, the bar 3, its eyes 2, rod 4, crank 5, shaft 6, and means to rotate said shaft to reciprocate said bar, feed-rollers to draw the thread from the beam under the guidance of 80 the raddle and the reciprocating bar, and the spindles and means to drive them.

5. The bobbin-carrying spindles and means to rotate them, and the traverse - rail and means to actuate it, and the feed-rolls located 85 above the tops of the spindles and arranged lengthwise of the machine, and with relation to the rows of spindles and bobbins, and means to rotate the feed-rolls, combined with a raddle and a warp-beam, the longitudinal axis of 90 latter being extended in the direction of the length of the machine and feed-rolls, substantially as described.

6. The bobbin-carrying spindles arranged in rows at each side the center of the machine, and traverse - rail, combined with feed-rolls having their longitudinal axes arranged in the direction of the length of the rows of spindles, and at a point above or higher than the tops of the spindles, and between the rows of spindles at opposite sides of the machine, and with means to rotate the spindles and feed-rolls and reciprocate the traverse-rail, the arrangement of the feed-rollers with relation to the spindles being such as to enable the threads to be led 100 from the feed-rolls in opposite directions down to the traverse-rail and spindles, substantially as described.

7. The combination, with the feed-rolls of a machine to wind yarn upon filling-bobbins, of 105 spindles provided with flanges, bolster-cases, loose whirls, intermediate friction-washers, means to rotate the said whirls, the traverse-rail, means to actuate it, the feed-rolls being located above the tops of the spindles and arranged lengthwise of the machine, as described, with relation to the row of spindles, and means to rotate the feed-rolls, and a raddle and yarn-beam, the longitudinal axis of 115 the latter extending in the direction of the axes of the feed-rolls, all substantially as and for the purpose set forth.

In testimony whereof I have signed my name to this specification in the presence of two subscribing witnesses.

HERMAN F. STRAW.
